UNITED STATES PATENT OFFICE.

JEAN RÜEGG, OF FELDBACH, NEAR ZURICH, SWITZERLAND.

REEL.

Application filed December 20, 1926, Serial No. 156,030, and in Switzerland July 20, 1926.

My invention relates to reels and has for its object to provide reels having hank-supporting members of great elasticity in order to permit hanks of either material to be treated.

The drawing illustrates an embodiment of the subject of the invention, the hank-carrying members of which are so formed that the diameter of the reel can be modified 10 within far greater limits than is the case with known reels.

Fig. 1 shews a median radial section of the reel, adjusted to its minimum diameter.

Fig. 2 is a plan of the reel certain portions 15 having been omitted and others shown in section.

Fig. 3 represents a median radial cross section of a portion of the reel, adjusted to approximately its greatest diameter. In 20 order to simplify the drawing and make it clearer, only one of each of the eight similarly constructed hank-carrying members of the reel is shewn completely in Figs. 1 and 2.

25 The reel illustrated has two pairs of spoke wheels *a*, *b*. The wheels *a* are secured together by means of screw bolts *c* and nuts *d* and are adapted to rotate on the shaft *e*. The wheels *b* are attached to a wooden hub *f* 30 which turns with the shaft *e*. The two wheels *a* can be rigidly clamped to the hub *f* by means of a wing nut *g*, so as to turn along with the inner wheels *b*.

Each of the hank carriers *h*¹, *h*² . . . *h*⁸ 35 consists of two wires *i*, the inner end of which is inserted on the inner face of the one of the two wheels *b*, and is secured by a nut *k* on the outer face of same, though adapted to swing in the wheel. Beyond the rim of 40 the wheels, these wires *i* are bent round in the shape of a bow over the rim of the adjacent wheel *a*. The outer end of each wire carries a spiral spring *l*, to which is attached a thinner wire *m* connecting the two springs 45 *l* belonging to the same hank carrier and forming the yarn support *n*. This latter is bent backwards in relation to the direction of rotation of the reel (see arrow Fig. 1) and out of alignment with the plane of the 50 rest of the hank carrier as fixed by the position of the two wires *i*. Consequently, it tends to give way in an inward direction, as indicated by the broken line in Fig. 1 under the pull of the hank, but has no tend-

ency to tilt in the other direction so as to 55 increase the distance between the support *n* and the axis of the reel. The inward and rearward deflection of the support *m*, *n* could evidently be carried much further than indicated by the broken line in Fig. 1. 60

Each of the bolts *c*¹, *c*² . . . serves to support and guide a pair of wires *i*. Moreover, for the purpose of guidance, a ring *o*, loosely surrounding the bolt and the wire, so as to allow free relative movement, is provided at 65 each point of support. The wires *i* are formed in such a way that, in order to reduce the diameter of the reel to its smallest dimensions, they can be shifted in the inward direction until they touch the wooden 70 hub *f* or nearly so (Fig. 1); whilst, on the other hand, the two pairs of wheels *a* and *b* can be turned in relation to each other (by about 150°) to such an extent that a given bolt *c* can reach a position very close to the 75 pivotal point of the hank carrier *h* which it guides, and said carrier can assume an approximately radial position, with practically its whole length projecting beyond the rim of the wheels (Fig. 3).

The form of yarn carrier allowing this wide range is shewn for the carrier *h*¹ in Fig. 2. In Fig. 1 this latter is assumed to lie in a horizontal position. In this position, corresponding to the smallest diameter 80 of the reel, it is crossed by the six other carriers which do not lie parallel with it (as is the case with *h*⁵), but extend from the upper half of the reel to the lower and vice versa. The two wires *i* belonging to said carrier are furthest apart at the part 1 situated nearest their point of attachment *k* to the wheel *b*; and it is between this widest distance that the narrowest part of the carrier *h*⁶ passes. The wires *i* are bent closer 85 together at 2, to form a narrower part 3 of the carrier. Here the narrowest parts of the carriers *h*⁷ and *h*⁸ also pass between the wires of *h*¹. At approximately the vertical axial plane of the reel, the wires *i* are again bent 90 inward at 4 and, from this point to the point at which they are bent out to a bow, they form the narrowest part 5 of the carrier *h*¹. The widest parts of the carriers *h*², *h*³ and *h*⁴ 95 pass outside this part 5. If, therefore, the pair of wheels *a* be turned, in the direction of the arrow, out of the position shewn in Fig. 1, while the pair *b* remain stationary, 100 105

the carriers h^6 , h^7 , h^8 , which lie with their narrowest parts 5 in the wider parts 1 and 3 of the carrier h^1 , will swing leftward and outward along said wider parts, being carried round by the bolts c —with which they are loosely connected by means of the rings o —whereas their pivotal axis at k remains stationary with the inner wheels b . The carriers h^1 , h^2 , h^3 are swung towards the right, their midway parts 1 and 3 sliding outside the narrowest part 5 of the carrier h^1 . The same applies to all the other carriers. In the case of each of them the narrowest parts 5 of three other carriers slide inside their wider parts 1 and 3, on one side of the axial plane, whilst on the other side of said plane the wider parts of three other carriers slide outside the narrowest part and in the outward direction. In this manner, the several carriers pass by each other without restriction and are able, as shewn in Fig. 3 to assume an approximately radial position, in which, with the dimensions shewn, the effective diameter of the reel is more than double its original diameter. This arrangement enables all the different sizes of hanks met with to be wound on one and the same reel, instead of having to use 3 or 4 reels as theretofore. The number of hank carriers may, of course, be varied as desired. The wires i may be replaced by strips of metal, and the manner of mounting and guiding the carriers may differ from that represented.

35 What I claim is:

1. A reel comprising a number of hank carriers each composed of two bows of wire, the shanks of one of these bows being arranged in straight line with that of the other bow, a spiral spring connecting the corresponding shanks of such bows with one another, a yarn supporting part on the outer bow bent backward in the peripheral direction.

40 2. In a reel, two pairs of disks having the same axis of rotation, one pair being rotatable in relation to the other pair, bow-shaped hank carriers comprising each a pair of wires disposed in a plane parallel to the common axis of the disks, these wires having one end pivoted to one of said pairs of disks whilst near their other end they are slidably guided on the other pair of disks.

45 3. A reel comprising a shaft, a pair of outer wheels and a pair of inner wheels mounted on this shaft one of these pairs of wheels being rigidly connected to said shaft, whilst the other pair of wheels is rotatable thereon, bow-shaped hank carriers pivoted on one pair of wheels and slidably guided on the other pair of wheels at such a distance from the pivot that the carrier nearly touches the hub of the wheels, the said hank carriers being arranged between the wheels

50 the stems of the bows diminishes in steps from the pivot to the guiding point, within this section the wider part of each hank carrier being crossed interiorly by the narrower parts of preceding carriers, and its narrower part is crossed exteriorly by the wider parts of following carriers, in such a way that, when one of the pairs of wheels is rotated in relation to the other pair, in either direction, in various hank carriers can slide freely past one another and become uncrossed.

55 4. A reel comprising a shaft, a hub fixed on this shaft, two parallel disks fixed on this hub at a suitable distance one from another two other disks loosely mounted on said shaft on the outside of the two other disks, means for locking these outer disks in said hub at any desired position of the outer disks relatively to the inner disks, screw bolts rigidly connecting the outer disks one with another at a diameter greater than that of the inner disks, wires arranged in pairs between the two inner disks to form hank carriers, each of these wires being pivoted with one end to one of said inner disks and extending with its other end beyond one of said screw bolts which lies at a distance from the pivot corresponding to an angle of about 150° , the plane determined by any one of said pairs of wires intersecting that of a few preceding and following pairs, the wires of the same pair being bent at determined points in the direction one towards another in such a manner that the intersecting preceding carriers cross said pair between the wires thereof whilst the following hank carriers are crossing said pair on its outside, means being provided on said screw bolts for loosely guiding said wires.

60 5. A reel comprising two pairs of disks, an outer and an inner one, mounted on the same shaft and rotatable one pair relatively to the other pair, hank carriers each comprising two wires pivoted with one end to one of the disks of the inner pair, screw bolts rigidly connecting the disks of the outer pair, two guide rings mounted on each of these screw bolts so as to loosely surround this bolt and one of said wires to allow free movement of this wire in relation to the screw bolt during rotation of one of said pairs of disks relatively to the other.

65 6. A reel comprising strap-shaped hank-supporting members each composed of an outer and an inner part, springs interposed between these parts, the outer extremity of these springs being adapted to be bent laterally in any direction relatively to the inner extremity of the spring so as to permit the outer or yarn-supporting part of said members to spring relatively to the inner part in peripheral direction.

70 7. A reel comprising hank-supporting members each composed of an outer and an in-

ner part, a spring connection between said inner and outer parts, the outer extremity of this spring connection being adapted to be bent laterally in any direction relatively to the inner extremity thereof, said outer part of the hank-supporting member being directed backward relatively to the axis of the

spring connection and to the direction of rotation of the reel so as to ensure it to spring backward under the pull of the hank. 10

In testimony whereof I have affixed my signature.

JEAN RÜEGG.
